Inventor:

Chas Spofford

United States Patent Office.

CHARLES SPOFFORD, OF BOSTON, MASSACHUSETTS, ASSIGNOR TO CHARLES SPOFFORD, WALTER E. HAWES, CHARLES HERSEY, AND FRANCIS E. HERSEY, OF SAME PLACE.

Letters Patent No. 70,911, dated November 12, 1867.

CAR-BRAKE.

The Schedule referred to in these Letters Patent and making part of the same.

TO ALL WHOM IT MAY CONCERN:

Be it known that I, CHARLES SPOFFORD, of Boston, in the county of Suffolk, and State of Massachusetts, have invented certain Improvements in Brakes for Railroad Cars and other carriages, of which the following is a full, clear, and exact description, reference being had to the accompanying drawings, making part of this specification, in which—

Figure 1 is a plan of the upper side of the truck of a railroad car with my improvements applied thereto.

Figure 2 is a plan of the under side of the same.

Figure 3 is a section on the line $x-x$ of figs. 1 and 2.

Figure 4 is a section on the line $y-y$ of figs. 1, 2, and 3.

My invention relates to certain improvements in the mechanism for operating the brakes of railroad cars and other carriages, and consists in eccentric-gear in connection with an arm for operating the levers by which the brakes are brought in contact with the wheels, whereby the length of the leverage is increased, and the required amount of friction produced in a rapid manner by a gradual application of the power, and without the necessity of turning the brake-wheel an entire revolution.

My invention furthermore consists in taking the power directly from the car-wheel to bring the brake against it, by the employment of a friction-wheel which is thrown in contact therewith by a new combination of levers, one of which extends up from the floor or platform, and is operated by the hand of the brakeman.

To enable others skilled in the art to understand and use my invention, I will proceed to describe the manner in which it is carried out.

In the said drawings, A is the truck of a railroad car, in suitable bearings, a , in which revolve the shafts B, which carry the wheels C. To a standard, D, secured at b to the under side of the truck, is pivoted, at c , a long lever, E, to which, at d e , are secured the inner ends of two arms or rods, F G, the outer ends of these rods being attached at f g to the brakes H I, one method of operating which will now be described.

J is a bar or rod, one end of which is secured at h to the lever E, the other end of the rod being connected by a cord or chain, i , to the outer end of an arm, K, secured to the bottom of a short vertical shaft, L, to the top of which is fixed an eccentric-gear, M, which engages with an eccentric-gear, N, of corresponding size and form, secured to the bottom of a vertical shaft, O, which is revolved in the direction of the red arrow, by power applied to the brake-wheel P. As the eccentric-gear N turns that, M, the resistance to be overcome is but slight at first, and the brake is taken in rapidly, the resistance gradually increasing, and the distance through which the eccentric-gear move decreasing toward the end of the braking-up operation, the brake-wheel being turned only a partial revolution. The position of the eccentric-gear M N may be changed if desired, viz, they may be placed vertically instead of horizontally, and be operated by foot or by hand.

The second portion of my invention will now be described.

The inner face of each of the wheels C is recessed out for the reception of a circular disk, Q, as shown in figs. 2 and 3, the said disk being thrown out into contact with the surface of a wheel, C, by pressing down on the head k of an upright arm, R, connected at l to one end of a long lever, S, the other end of the lever being secured to a standard, m, which forms its fulcrum, two bifurcated arms, n o, provided with friction-sleeves p, being connected to each other, and the lever S at q, which, on being depressed, throws out the lower ends of the arms n o, causing the sleeve p to force the disk Q against the face of its wheel, which imparts its motion thereto, and in revolving winds up the cord or chain r, which connects the wheel with the end s of the lever E, and, through the connections above described, securely clamping the brakes H I upon the wheels. Instead of applying the friction of the disk Q directly to the face of a car-wheel, C, an intermediate wheel on its shaft B may be employed for receiving and transmitting the friction to the disk, if desired; but I wish it to be understood that I do not claim operating the brake by either of these last-described methods.

The third arrangement which I employ for operating the brakes will now be set forth.

T is a friction-wheel, the periphery of which is hollowed out to receive the flange t of one of the wheels C. This friction-wheel is secured to one end of a shaft, U, which is supported in bearings u v, secured to the under side of the framework, the bearing u being formed in an arm or bar, w, provided with slots z, through which

pass screws 6 into the framework. To the outer end of this arm is pivoted an upright lever or shipper, 7, which is operated by the brakeman.

By the construction above described, the arm may be instantly slid longitudinally in either direction, thereby throwing the friction-wheel in and out of contact with the car-wheel to which it is applied. When the friction-wheel T embraces the car-wheel, and is revolved simultaneously therewith, a cord or chain, 8, connecting the lever E with the shaft U, is wound around thereon, thus operating both brakes.

Claim.

What I claim as my invention, and desire to secure by Letters Patent, is—

The eccentric-gear M N, when used with mechanism for operating the brakes of railroad cars, etc., substantially as described.

I also claim the friction-wheel T, in combination with a slotted bar, w, and shipper 7, for taking the power from the periphery of a car-wheel, C, to wind up the brake, substantially as set forth.

CHAS. SPOFFORD.
